[57] CLAIM

The ornamental design for a spur pad, substantially as shown and described.

DESCRIPTION

FIG. 1 is a front perspective view of a spur pad showing my new design;

FIG. 2 is a front elevational view thereof, the rear being substantially plain and unornamented;

FIG. 3 is a bottom plan view of FIG. 2;

FIG. 4 is a side elevational view, the opposite side being a mirror image thereto.
